No. 37,258.

Patented December 6, 1904.

UNITED STATES PATENT OFFICE.

ALBERT S. WAITZFELDER, OF NEW YORK, N. Y., ASSIGNOR TO THE KURSHEEDT MANUFACTURING COMPANY, OF NEW YORK, N. Y., A CORPORATION OF NEW YORK.

DESIGN FOR TRIMMING.

SPECIFICATION forming part of Design No. 37,258, dated December 6, 1904.

Application filed October 8, 1904. Serial No. 227,726. Term of patent 3½ years.

To all whom it may concern:

Be it known that I, ALBERT S. WAITZFELDER, a citizen of the United States, residing in the borough of Manhattan, city, county, and State of New York, have invented a certain new, original, and ornamental Design for a Trimming, of which the following is a specification, reference being had to the accompanying drawing, forming a part hereof.

10 In the drawing the figure shows my design for a trimming.

What I claim as new, and desire to secure by Letters Patent, is—

The ornamental design for trimming, substantially as herein shown.

ALBERT S. WAITZFELDER
